UNITED STATES PATENT OFFICE.

KENYON SKEEN, OF KANSAS CITY, MISSOURI.

GATE.

SPECIFICATION forming part of Letters Patent No. 361,331, dated April 19, 1887.

Application filed February 21, 1887. Serial No. 228,411. (No model.)

To all whom it may concern:

Be it known that I, KENYON SKEEN, a citizen of the United States, residing at Kansas City, in the county of Jackson and State of Missouri, have invented a new and useful Improvement in Gates, of which the following is a specification.

This invention relates to improvements in gates; and it consists in certain novel features ¹⁰ hereinafter described and claimed.

In the accompanying drawings, Figure 1 represents a plan view of the whole mechanism with the tops of the embedded cases broken away in such manner as to show the internal mechanism. Fig. 2 represents a side view of ¹⁵ the gates. Fig. 3 represents a sideview of one leaf, the angle-iron to which it is secured, and the case in which said iron is pivoted, the case having its side removed to show the connected parts. Fig. 4 represents a central vertical ²⁰ longitudinal section of the case, showing the angle-iron and the parts connected with it in a reversed position. Fig. 5 represents an end view of the angle-iron with the corresponding case in section, showing the interior parts looking ²⁵ from the outer side. Fig. 6 represents a perspective view of the vertical shaft and attached arms. Figs. 7 and 8 represent vertical longitudinal sections of one of the lever-cases, taken on opposite sides of the central partition, to show the attachment of the levers and ³⁰ corresponding link-rods.

Referring to the accompanying drawings by letter, A designates two similar rectangular leaves of a double gate, each having its lower outer corner, a, secured in an angle-iron, B, hereinafter described, by screws or otherwise, as shown. The leaf has a weight, a', in the form of an angle-iron attached to its upper inner corner, for a purpose hereinafter explained.

C are posts standing on one side of the gate-leaves opposite the center of the angle-iron, and each having on the side adjacent to the leaf a long guide-staple, c, through which passes the wire c', which runs diagonally across the side of the leaf from its lower edge to its rear edge, the ends of the wire being turned inward and secured in the leaf. The said wire ⁴⁵ and the staple on the adjacent post serve to steady and guide the leaf when it swings on

its corners a, as described. Each angle-iron B has a shaft, b, passing through or secured to its angle and journaled in bearings in the sides of the case or box b', which is sunk into ⁵⁵ the earth, and upon the arms of said shaft, between the angle-iron and case, are the anti-friction rollers b², which serve a purpose hereinafter explained.

Depending from the angle-iron within the ⁶⁰ case, in a line bisecting its angle, is the bifurcated extension b³, between the arms of which is pivoted the outer end of a link-rod, D, a pin, d, passing through openings in the ends of said arms and through a short longitudinal slot, d', ⁶⁵ in the rod D.

Attached at one end to the inner part of the floor of the case b', and at the other end to the end of the pin d, on one side of the bifurcated extension b³, is a spring, d², which curves over ⁷⁰ the pin from its outer side before attachment thereto.

d³ is a spring similar to the spring d², and attached at one end to the opposite end of the pin d and at the other end to the outer part of ⁷⁵ the floor of the case, curving over the pin from its inner side. The springs d² d³ therefore act in opposite directions, and are kept from touching the shaft b by the rollers b², upon which they impinge and which reduce the ⁸⁰ friction of their motion.

When the angle-arm has its arms at angles of forty-five degrees to the surface of the ground, the bifurcated lever stands vertically downward, and the springs d² d³ are neither ⁸⁵ expanded nor contracted. In this position the leaf would have its inner upper corner vertically above the corner a, so that the weight a' would not tend to move the leaf either way; but when the said weighted corner is on one side of ⁹⁰ the corner a, the weight comes into play and causes the leaf to fall toward that side, whether inward or outward. In so falling the leaf goes down easily and without jar, for although the leverage of the weight is constantly increasing, ⁹⁵ the springs d² d³ are being put under more and more tension, one in expanding and the other in contracting, the parts being so arranged that the leverage of the weight at all times has just a little more power than the combined tensions of the springs. When the leaf falls inward or ¹⁰⁰ closes, the spring d² is put under tension while

contracting and the spring d^3 while expanding. When the leaf falls outward or opens the reverse is the case.

The mechanism by which the leaves of the gate are simultaneously operated is constructed as follows: E is a rectangular case or box sunk in the earth midway between the cases $b^1 b^1$, and e is a vertical shaft journaled centrally in the upper and lower surfaces of the same. $e' e'$ are opposite similar arms standing from the shaft e in the direction of the length of the road, and having the inner ends of the corresponding link-rods, D D, pivoted in their bifurcated ends within the case E. $e^1 e^1$ are similar opposite arms standing from the shaft e transversely to the road and below the arms e' . As the mechanism connected with said arms is the same on each side, a description of one side only is necessary.

Within the bifurcated end of one arm e^1 is pivoted one end of a link-rod, f, the other end of which is bifurcated and pivoted upon a lever, F.

G is a case or box situated a suitable distance along the road from the case E, and provided with a central longitudinal partition, g, between which and one side of the case is pivoted the lower end of the lever F.

To the opposite arm e' to that which is connected to the link-rod f is similarly connected a link-rod, h, the opposite end thereof being pivoted to the lower end of a lever, H, which is pivoted a proper distance above said end between the partition g and the side of the case E opposite that to which is pivoted the lever F. The levers F and H and corresponding link-rods are pivoted on opposite sides of the partitions g on the opposite sides of the gate.

I is a trip-rod running entirely across the road and between the levers F and H, the former being on the outer side, the latter on the inner side thereof. The rod I has its end portions bent at right angles to its shaft and its ends again bent parallel therewith and journaled in bearings i i, made on a standard, i', on one side and in the side of a case, J, on the other side, the said case being sunk a proper distance in the earth. The end of the rod I within the casing is bent at right angles to the part forming the corresponding journal and has secured to it a weight, j, which keeps the rod I raised at all times except when depressed by the wheel of a vehicle.

The operation of the invention is as follows: The leaves being swung inward or closed, the inner arms of the angle-irons are horizontal and their outer arms vertical, and the bifurcated extensions b^3 are inclined outward, forcing the pins d into the outer ends of the slots d' of the levers D, which can consequently have no longitudinal movement inward without turning the bifurcated extensions inward and the angle-irons outward. Also, during the closed position of the leaves the rods D, arms e' and e^1 , and link-rods f and h hold the

levers F depressed and the levers H raised. When a vehicle-wheel then approaching the gate from either side depresses the trip-rod, the latter depresses the lever H, which, by means of its link-rod and the arm e^1 on the shaft e, rotates the latter. The shaft, by means of its arms e' , draws inward the rods D, rotating, as described, the angle-irons and leaves outward till the weighted corners of the latter will be a little outward from their corners $a a$. The leverage of the weight then coming into action, as described, causes the gate to fall outward, putting the springs $d^2 d^3$ under constantly increasing tension. The leaves are now entirely open and the shaft e is rotated by the rods D in the direction that raises the levers F and depresses the levers H. The pins d, also, are forced into the inner ends of the slots d' . The vehicle, having now passed the gate, depresses the trip-rod on the opposite side. The latter depresses the corresponding lever F, and by means of the link-rods f, shaft e, arms e' and e^1 , and link-rods D, which are moved outward, the leaves are moved inward till their weighted corners are a little inward from the corners a . The leaves then close themselves. The springs $d^2 d^3$, being under strong tension when the leaves are either closed or opened, assist very materially in the operation, so that very little power is needed to depress the trip-rods. After the trip-rod has been depressed and the wheel has passed it, it is immediately raised by the action of the weight f.

Having described my invention, I claim—

1. The combination of the opposite similar gate-leaves, the angle-irons secured to the outer lower corners thereof and each having its central transverse shaft journaled in bearings in the sides of a case sunk in the earth, the extensions depending from the angles of the angle-irons and each having a transverse pin in its ends, the oppositely-acting springs attached to said pins in such manner that each pin has the end of a spring secured to each of its ends, the two springs bending around the pin in opposite directions, so that when the corresponding angle-iron is rotated in either direction from a position in which its arms stand at angles of forty-five degrees to the ground one spring will be put under tension while its coil is expanding and the other while its coil is contracting, the weights secured to the inner upper corners of the leaves, each weight having a leverage slightly greater than the tensions of the corresponding springs, and mechanism, substantially as described, whereby the angle-irons may be rotated in either direction a short distance past the said position in which its arms stand at angles of forty-five degrees, substantially as specified.

2. The combination of the opposite gate-leaves, the pivoted angle-irons having the bifurcated extensions depending from them, the link-rods pivoted at their inner ends to the opposite arms of the central vertical shaft and

having slots in their outer ends, the pin passing through said slots and through openings in the bifurcated extensions, the oppositely-acting springs having their ends attached to 5 said pins and bending around them in opposite directions, the weights on the upper inner corners of the leaves, the central vertical shaft, and mechanism, substantially as described, whereby the said shaft can be rotated from 10 either side by the wheels of an approaching vehicle in the direction to open the leaves till their weights are a little outward from their pivotal corners *a* and after the vehicle has passed the gate in the direction to close 15 the leaves till the weights are a little inward from said corners, substantially as specified.

3. The combination, with the leaves, angle-irons having bifurcated extensions, pins, springs, slotted or link rods D, and weights 20 on the leaves, all constructed substantially as specified, of the vertical shaft *e*, provided with the two sets of arms *e'* and *e''*, at right angles to each other, and with the arms *e'* pivoted to the inner ends of the link-rods D, the link-

rods *f* and *h*, pivoted to the arms *e'*, the levers 25 F, each pivoted at its end between the central partition and one of the sides of a case, G, and having the outer end of the corresponding link-rod, *f*, pivoted upon it a suitable distance above said end, the levers H, each having the 30 corresponding link-rod, *h*, pivoted upon its lower end and itself pivoted in the case G, between the partition and the side of the case opposite that on which the lever F is pivoted, and the trip-rods I, running between the corresponding levers, F and H, as described, journaled in the bearings *i i* on the standard *i'* and case J, respectively, and having the weight 35 *j* attached to its depending end within the case J, substantially as specified. 40

In testimony that I claim the foregoing as my own I have hereto affixed my signature in presence of two witnesses.

KENYON SKEEN.
